(57) **CLAIM**

The ornamental design for an expandable corner shelf, as shown and described.

DESCRIPTION

FIG. 1 is a perspective view of an expandable corner shelf in the extended position showing my design;

FIG. 2 is a top plan view thereof;

FIG. 3 is a front side elevational view thereof;

FIG. 4 is a rear side elevational view thereof;

FIG. 5 is a bottom plan view thereof;

FIG. 6 is a right side elevational view thereof, the left side being a mirror image.

FIG. 7 is a perspective view of an expandable corner shelf in the retracted position;

FIG. 8 is a top plan view thereof;

FIG. 9 is a front side elevational view thereof;

FIG. 10 is a rear side elevational view thereof;

FIG. 11 is a bottom plan view thereof; and,

FIG. 12 is a right side elevational view thereof, the left side being a mirror image.
